UNITED STATES PATENT OFFICE.

WILLIAM E. ELLIOTT, OF GRAND RAPIDS, MICHIGAN, ASSIGNOR TO AMERICAN
BUTTON & FASTENER COMPANY, A CORPORATION OF MAINE.

MOUNT FOR NAILS OR THE LIKE.

1,337,212.

Specification of Letters Patent. Patented Apr. 20, 1920.

Application filed January 17, 1918, Serial No. 72,650. Renewed May 21, 1918. Serial No. 235,898.

To all whom it may concern:

Be it known that I, WILLIAM ELLIOTT, a citizen of the United States of America, residing at Grand Rapids, in the county of Kent and State of Michigan, have invented certain new and useful Improvements in Mounts for Nails or the like; and I do hereby declare the following to be a full, clear, and exact description of the invention, such as will enable others skilled in the art to which it appertains to make and use the same.

This invention relates to mounts for nails, tacks, or the like, and it is an important object of the invention to provide a mount such that a large number of articles may be mounted in predetermined relation in a small space, retained on the mount against accidental displacement, and yet be readily removed when desired for use.

The features of the invention will be understood from a consideration of the following description of an illustrative embodiment thereof as shown in the accompanying drawing, in which,

Figure 1 is a perspective view of a section of a package containing nails and constructed according to the invention.

Fig. 2 is a view of the mounting strip before it has been bent to receive and secure in place the articles, such as nails; and

Fig. 3 is a transverse section taken on the line 3—3 of Fig. 1.

Like reference characters refer to like parts throughout the several views of the drawing.

The nails, for example, which are to be attached to the mounting strip are constructed with a shank 1 and a head 2. In the illustrated embodiment, these nails are attached to a long, narrow and thin strip of flexible material, preferably, paper, and are located side by side and as closely adjacent each other as is possible. The strip 3 comprises a middle part 3 at each side of which are projections or ribs 4 and 5 as shown in Figs. 1 and 3, the rib 4 being formed by bending the paper on lines *a* and *c* and the latter on the lines *e*, *g* and *m* indicated in Fig. 2 so that below the projection 5 a comparatively wide extension 6 is left on the strip. At the opposite side of the strip a plurality of tongues 7 are formed by cutting inwardly the slots 8 which are

located at an acute angle to the edges of the strip and substantially parallel to the intended direction of insertion of the nails.

The shanks of the nails or tacks are forced through the projections 4 and 5 and are located with reference to the outer edge of the section 6 so as to make an acute angle therewith. In this manner the head of a nail may be caused partially to overlap the head of an adjacent nail at one side and to be in turn partially overlapped by the head of the adjacent nail at the opposite side thus permitting a close positioning of the nails which could not be had if the shanks of the nails were located at right angles to the edges of the strip. The tongues at 7 are turned up over the heads of the nails and preferably are formed into substantially U-shaped members as indicated in Fig. 3, making a guard for the heads of the nails to retain them against accidental displacement from the mount, the outer portions of the tongues 7 coming over the heads of the nails, one tongue being provided for each nail or tack.

The construction for mounting nails or tacks as thus disclosed permits the mounting of a large number of nails or tacks in a continuous row and at the same time the long extension 6 below the ends of the shanks 1 affords a surface which may be grasped by any suitable mechanism for withdrawing the mount from the nails or tacks, the heads of the said articles being held or engaged in any suitable manner as the strip is withdrawn therefrom. Furthermore, the division of the guard into a plurality of tongues 7 assists the coiling of the strip into a compact package. It is contemplated that a strip of indefinite length thus wound and having a large number of nails or tacks thereon may be used in automatic nailing machines and that the heads may be engaged in any suitable raceway while the extension at 6 may be grasped by any suitable mechanism to assist the separation of the paper strip and the nails or tacks. Each nail or tack as it is withdrawn will affect only its section of the mount since each tongue 7 will bend outwardly as the corresponding nail or tack is withdrawn.

I claim:

1. In combination, an elongated mounting strip having spaced apart upstanding pro-

- jections extending lengthwise of the strip, and a plurality of articles having shanks and heads, said shanks passing through the projections and being located at an acute angle thereto and with the heads of the articles partially overlapping one another. 5
2. In combination, an elongated mounting strip having spaced apart projections extending lengthwise of said strip, and a plurality of articles having shanks and heads, said shanks passing through the projections and being located at an acute angle thereto and with adjacent heads of said articles partially overlapping, said strip at 10 one edge being formed into a U-shaped trough to receive and partially cover the heads of said articles.
3. In combination, an elongated mounting strip having spaced apart upstanding projections extending lengthwise of the strip, a plurality of articles each comprised of a shank and head, said shanks passing through the projections and located at an acute angle thereto with adjacent heads of said articles 15 partially overlapping, and means formed on the mounting strip to resist the withdrawal of said articles from the mounting strip.
4. In combination, an elongated mounting strip having spaced apart upstanding projections formed lengthwise of the strip, a plurality of articles each having a shank and head, said shanks passing through the projections and located at an acute angle thereto with adjacent heads of said articles 20 partially overlapping, and an extension to the mount at each side of the strip, one of said extensions formed as a flat section projecting a distance beyond the ends of the shanks, and the other formed into a U-shaped portion to receive and partially cover the heads of the articles and serving to retain them on the strip against displacement. 25
5. In combination, an elongated mounting strip having spaced apart upstanding projections formed lengthwise of the strip, a plurality of articles each having a shank and a head attached to the strip by passing the shanks through said projections, at an acute angle thereto and with the heads of 30 adjacent articles partially overlapping, and an extension at one side of the strip adjacent the heads formed into a substantially U-shaped portion to receive and partially cover the heads, said extension being cut at 35 a plurality of points to form individual U-shaped tongues receiving and partially covering each head.
6. In combination, a mounting strip, a plurality of articles having shanks and 40 heads disposed across the face of the strip at an acute angle to the length of said strip, and means for securing the articles to the strip. 45
7. In combination, a mounting strip, a plurality of articles having heads and shanks disposed across the face of said strip at an acute angle to the length of the strip, said strip being of greater width than the length of said articles whereby a section of the strip is left uncovered beyond the ends 50 of said articles, and means for securing the articles on the strip. 55
8. In combination, an elongated mounting strip having spaced, upstanding projections extending lengthwise of the strip, and a plurality of articles having shanks and heads, said shanks passing through the projections and being located at acute angles thereto. 60
9. In combination, an elongated mounting strip having spaced longitudinal ribs, and a plurality of articles having shanks and heads, said shanks being passed through the ribs and located at acute angles thereto, said strip at one edge being turned up over 65 the heads of the articles to resist their removal from the strip. 70
10. In combination, an elongated mounting strip having spaced projections extending lengthwise of said strip, and a plurality of articles having shanks and heads, said shanks passing through the projections and being located at acute angles thereto and with the heads of the adjacent articles partially overlapping, said mount at one edge 75 being turned up to cover the heads of the articles and resist their removal from the mounting strip. 80
11. In combination, an elongated mounting strip having spaced upstanding projections extending lengthwise of the strip, a plurality of articles each comprised of a shank and head, said shanks passing through the projections and located at acute angles thereto, and means formed on the mounting 85 strip to resist the withdrawal of said articles from the strip. 90
12. In combination, an elongated mounting strip, a plurality of articles having shanks and heads disposed across the face of the strip at acute angles to the length of said strip, and means for securing the articles to the strip, said strip near one side thereof being turned up over the heads of the articles and being cut to form individual 95 tongues adjacent to each head. 100
13. In combination, an elongated mounting strip provided with spaced apart longitudinal ribs, and a plurality of articles each having a shank and head, said shanks being 105 passed through said ribs and located transversely of the strip, a portion of said strip at the edge adjacent to the heads of the articles being extended and bent around said heads of the articles to resist their withdrawal from the strip. 115
14. In combination, an elongated mounting strip provided with spaced apart longi- 120

tudinal ribs, a plurality of articles each having a shank and head, said shanks being passed through said ribs and located transversely of the strip, and said strip along one side being extended and bent around the heads of the articles to resist their withdrawal from the strip, said extension being slit along lines substantially parallel to the direction of the shanks of the articles to form individual tongues opposite the head 10 of each article.

In testimony whereof I affix my signature.

WILLIAM E. ELLIOTT.
